(57) **CLAIM**

The ornamental design for the display screen with animated graphical user interface, as shown and described.

DESCRIPTION

FIG. 1 is a front view of display screen with animated graphical user interface showing the first image in a sequence;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a seventh image thereof; and,

FIG. 8 is an eighth image thereof.

The appearance of the animated graphical user interface sequentially transitions between the images shown in FIGS. 1-8. The process or period in which one image transitions to another image forms no part of the claimed design. The broken line rectangle illustrates a display screen and forms no part of the claimed design. The remaining broken lines illustrate portions of a graphical user interface and form no part of the claimed design.
